FOLLOW BOARD

Filed Sept. 21, 1923

UNITED STATES PATENT OFFICE.

PETER VAN VLASSINGEN, OF CHICAGO, ILLINOIS, ASSIGNOR TO SYCO SYSTEMS COMPANY, OF CHICAGO, ILLINOIS, A CORPORATION OF ILLINOIS.

FOLLOW BOARD.

Application filed September 21, 1923. Serial No. 663,941.

To all whom it may concern:

Be it known that I, PETER VAN VLASSINGEN, a citizen of the United States, and a resident of Chicago, in the county of Cook and State of Illinois, have invented certain new and useful Improvements in Follow Boards, of which the following is a specification.

This invention relates to improvements in follow boards for filing cases or the like, and has for its principal object, to provide a new and improved device of the character described, which is simple in construction and capable of being readily adjustable to vary the capacity of the filing case or drawer. Other objects of invention will appear from time to time as the description proceeds.

The invention may best be understood by reference to the accompanying drawing, which illustrates one form in which it may be embodied.

In the drawing:

Fig. 1 is a view in perspective of a filing case provided with my improved follow board.

Fig. 2 is a transverse sectional view of the filing case shown in Fig. 1.

Fig. 3 is a longitudinal sectional view of the case.

Fig. 4 is an enlarged detailed view, in perspective, of the follow board.

Referring to the details of the drawings, my invention is shown as applied to a filing case 10, such as may be used for holding indexed cards, papers or the like, although it will be understood that the invention may also be applied to filing cabinets, drawers or the like.

The follow board comprises an upright member 11, extending across the case and adapted in practice to maintain the material in a compact body adjacent the front end of the case. The board is adjustable to various positions in the case by means of a projection or tongue 12, extending into a longitudinal slot 13 formed in the bottom 22 of said case. Said tongue is suitably secured at the forward margin of the board in the form shown and is flared outwardly at opposite sides thereof to fit in co-operating inclined surfaces 14, 14 of the slots. Thus, when the board is in position transverse of the case the tongue is free to slide longitudinally therein, but retains the board

in the case. In the preferred form shown, said tongue is made of a semi-flexible material, such as leather.

The board is provided with a relatively wide base, as indicated at 17, which provides a support therefor in co-operation with the tongue 12 when rearward pressure is applied, as for instance, by papers or the like in the case. Such pressure has a tendency to tip said board rearwardly, about the rear margin 18 of the base, but is resisted by the wedge shaped tongue 12, secured in the slot as described.

Suitable retaining members are provided for holding the follow board in adjusted position longitudinally of its case. In the form shown, these members comprise a pair of pins 20, 20 projecting from the bottom of the base 17 adjacent opposite ends thereof and adapted to register with a series of co-acting recesses 21, 21 in the bottom 22 of the case.

The parts are preferably arranged so that the front surface 23 of the follow board is inclined rearwardly when the base 17 is resting flatly on the bottom of the case as shown in Fig. 2, with the pins 20, 20 in interlocking engagement with a pair of recesses 21, 21. When in this position it will be observed that the tongue 12 is in close wedging engagement in the slot 13 so as to resist any rearward pressure on the board tending to rock it on the rear margin 18 of its base 17. The board is thus securely held in place while in position to hold papers or the like, but when it is desired to move the board longitudinally of the case, the board may be tilted forwardly until the pins 20, 20, are released from their respective recesses, in which position the tongue 12 is loosened in its engagement in the slot 13 so as to permit the board to be moved bodily along the case into any desired position, where pins 20 are again engaged in another pair of recesses 21, 21. An inclined or chamfered surface 24 is preferably provided at the front margin of the base 17, in order to permit the board to be freely tilted forwardly in releasing the tension upon the tongue 13, thus permitting the board to slide easily during its adjustment.

The flexibility of the tongue further aids in the ready manipulating of the board in the manner described. The board may be entirely removed from the case by turning 110

it at an angle to the case, thus allowing the tongue 12 to be withdrawn from slot 13.

Although I have shown and described one form in which my invention may be embodied, it will be understood that many changes in form and construction will occur to those skilled in the art without departing from the spirit and scope of my invention. I do not therefore wish to be understood as limiting myself to the construction shown and described herein, excepting in so far as specifically defined in the appended claims.

I claim:

15. 1. In a filing case having a bottom provided with a longitudinally disposed slot, a follow board having a base, interlocking surfaces on said base adapted interlockingly to co-act with other surfaces at a plurality of positions along said case bottom when said board is in normal upright position, and a flat flexible tongue projecting downwardly adjacent the forward margin of said base and having laterally extending 20 margins inserted through and engaged transversely of said slot, to secure said tongue against vertical movement therein, whereby said board may be released for 25 adjustment longitudinally of the case by 30 tilting the same forwardly.

2. In a filing case, a bottom provided with a longitudinal slot wider at its bottom than at the top thereof, a follow board having a base provided with a plurality of projections, a series of co-acting recesses in said case bottom adapted to be engaged by said projections, and a flexible tongue projecting downwardly adjacent the forward margin of said base, said tongue being secured flatwise of the board and having wedge shaped lateral margins fitting transversely of said slot, and affording longitudinal adjustment of the board when the latter is tilted forwardly, to release said projections from their respective recesses. 35 40

3. In a filing case, a bottom provided with a longitudinal slot, a follow board having a base provided with a plurality of projections, a series of co-acting recesses in said case bottom adapted to be engaged by said projections, and a tongue projecting downwardly adjacent the forward margin of said base, said tongue having wedge shaped lateral margins fitting the sides of said slot and insertable in said slot when the 50 board is turned at an oblique angle thereto. 55

In witness whereof, I hereunto subscribe my name this 15th day of September, A. D., 1923

PETER VAN VLISSINGEN.
